UNITED STATES PATENT OFFICE

MARTIN NYSTROM, OF CHICAGO, ILLINOIS, ASSIGNOR, BY MESNE ASSIGNMENTS, TO UNITED RESEARCH CORPORATION, OF LONG ISLAND CITY, NEW YORK, A CORPORATION OF DELAWARE

CABINET FOR ACOUSTIC DEVICES

Application filed October 19, 1927. Serial No. 227,177.

My invention relates to cabinets and more particularly to cabinets for acoustic devices.

One object of the invention is to provide a door mounted at the corner of a cabinet to swing through an angle of 270° so that it may be disposed along either of two adjacent sides of the cabinet.

Another object of the invention is to provide a pair of doors, one carrying an antenna, which are mounted at the corner of a cabinet to swing on a common axis through an angle of 270°.

A further object of the invention is to provide a concealed hinge for a cabinet door which will permit a large angular movement of the door.

A still further object of the invention is to provide a movable panel for a cabinet which may be swung outwardly to cause light to fall on a radio set.

A still further object of the invention is to provide a panel of the type described having a bull's eye for indicating when current is being supplied to a radio set or phonograph within the cabinet.

Other objects and advantages will become apparent as the description proceeds.

In the accompanying drawings forming a part of this specification

Fig. 1 is a perspective view of a combined radio and phonograph cabinet embodying my invention;

Fig. 2 is a plan view on an enlarged scale, of a corner of the cabinet shown in Fig. 1, doors being in open position to show the hinge structure and a wall of a compartment being broken away to show an antenna;

Fig. 3 is a sectional view taken on the line 3-3 of Fig. 2;

Fig. 4 is a sectional view taken on the line 4-4 of Fig. 1, and showing hinge structure and doors in closed position, the doors being broken away;

Fig. 5 is a vertical sectional view taken on the line 5-5 of Fig. 6 of a compartment showing the front door thereof in open position in dash lines;

Fig. 6 is a front elevational view of the door shown in Fig. 5, and an adjacent portion of the front of the cabinet;

Fig. 7 is a detail view of a device for securing the aforementioned doors together; and

Fig. 8 is a diagrammatic view showing the wiring connections between the pilot light, 55 the radio set and the electrical phonograph.

A cabinet embodying my invention may be provided with a compartment 1 for a loud speaker, not shown, and a record compartment 2 having a door 3.

A compartment adjacent to the record compartment receives a drawer 4 containing a radio receiving set 5, above which is a compartment 6 for an electric lamp 7.

A panel 8 for closing the compartment 6 65 is mounted on a suitable hinge 8' so that it may be swung to and retained in a partially open position to deflect rays from the electric lamp downwardly upon the receiving set.

The cabinet is provided with front doors 9 and 10 and a fixed top 11 may be disposed above the compartment 6, while a hinged top 12 may be arranged above a compartment 12' in which is located an electrical phonographic sound receiver 13 indicated diagrammatically in Fig. 8.

The side of the cabinet adjacent the radio receiving set compartment is provided with a recess 14 normally occupied by a door 14' on which is mounted an antenna 15.

A hinge plate 16 may be set into the top surface of the front door so as to lie flush therewith and may be secured by screws 17, a hinge plate 18 may be similarly secured to the side door. When the doors are in closed position the ends of the hinge plates extend outwardly, as shown particularly in Fig. 4. The front door may be cut away beneath the end of the hinge plate 16 and the hinge plate 18 may have a downward bend 19 therein so that its end may lie under the end of the hinge plate 16 when the doors are in closed position.

The hinge plates are supported on a common pivot on the outwardly directed end of a 95 supporting plate 20 which may be set into the under surface of the top 11.

As shown in Fig. 4 the inner corners of the doors are cut away so that the doors may be moved freely to the closed position where- 100

in their outer surfaces at the corner of the cabinet present a smooth and unbroken appearance. At the same time the hinges are concealed except at their ends which enhances very greatly the appearance of the cabinet.

It will be understood that the lower ends of the doors are likewise supported on a hinge 21 of the type described.

In Fig. 7 a device is illustrated for detachably securing together the doors 9 and 14'. This device comprises a spacer 22 carried by the front face of the door 9, an aperture 23 extends through the spacer and the door 9, and receives a latch 24 which has an operating head 25 at one end and a tooth 26 on the other. A fixed pin 27 extends through a slot 28 provided in the latch 24, the latch being adapted to pivot on said pin and also to slide relative thereto. The end of the latch may be inserted into an opening 29 in a plate 30 and a spring 31 may tend to force the latch 24 laterally so its tooth may be held in engagement with the plate 30. In order to disconnect the two doors, the latch 24 may be swung around the pin 27 against the action of the spring 31 and pulled inwardly to bring the tooth 26 past the inwardly extending ledge of the plate 30.

The doors may be moved separately or together through an angle of 270° and provide for convenient adjustment of the position of the antenna. The front door may be swung rearwardly to a position directly along the side of the cabinet when it is desired to conserve room.

The panel 8 is provided with an opening 33 in which may be positioned a sleeve 34, a flange 35 on the sleeve may be secured to the front of the panel. The sleeve 34 may be internally screw threaded to receive therein a screw threaded mounting 35' for a translucent bull's eye or window 36 which may serve, when the panel is closed, as a means to indicate whether the lamp 7 is on or off. A bracket 38 passing through an opening in the flange pivotally supports a ring 39 which serves as a handle for the panel.

As shown in Fig. 1, when the lamp 7 is glowing and the panel is in a partially open position, the light rays from the lamp will be deflected downwardly so as to fall on the receiving set 5 when the drawer is pulled out.

As indicated diagrammatically in Fig. 8, the lamp 7 is so connected to the source of electric energy that it will be illuminated only when the circuit of the radio receiving set or the electrical phonograph is closed. Switches 40 are provided for opening and closing the circuit. Hence, the lamp has a two-fold function, namely that of throwing a flood of light on the radio set and of acting as a means for indicating when the current of the radio set or the electrical phonograph is on.

While I have described a preferred form of my invention in detail, I do not wish to

be limited to the exact form shown, for many changes may be made within the scope of the invention as defined in the appended claims.

What I claim and desire to secure by Letters Patent is:

1. A rectangular cabinet having a door normally disposed along the side of said cabinet, a fixed wooden cabinet portion extending beyond the outer face of said door when in its normal position, a hinge member secured to said door and projecting outwardly beyond the outer face of said door and beyond the end thereof and pivoted at a corner of said cabinet below the lower face of said fixed portion, permitting said door to be swung through an arc of substantially 270° to a position along an adjacent wall of said cabinet.

2. A cabinet having a front door, a side door, an antenna on said side door, a hinge member on each of said doors, said hinge members having a common pivot offset from the corner of said cabinet and permitting movement of each of said doors through an angle of substantially 270° and means for releasably securing said doors together so that they may be moved in unison.

3. A cabinet having a front door, a side door, an antenna on said side door, a hinge member on each of said doors, said hinge members having a common pivot offset from the corner of the cabinet and permitting movement of each of said doors through an angle of substantially 270° and means including a manually controllable latch for securing said doors together so that they may be moved in unison.

4. A cabinet having a door normally disposed along a side of said cabinet, a second door normally disposed along an adjacent side of said cabinet, a portion of said cabinet extending over the top face of said doors, a flat hinge member for each of said doors secured to the top face thereof, each of said hinge members having an outwardly directed end supported on a common pivot on said cabinet portion to permit movement of said doors through an arc of substantially 270°.

5. A cabinet having a front wall, a drawer movable forwardly and rearwardly through the front of said cabinet, a radio set in said drawer, said drawer being at a height to permit convenient operation of said set by a person seated in front of said cabinet, a door normally extending in front of said cabinet when said drawer is closed, a second door normally extending along an adjacent side of said cabinet, and an antenna mounted on said second door and connected to said radio set, said doors being mounted to swing on a common axis and thus permit said person, when operating said radio set, to move said doors

in unison and adjust the position of said antenna.

6. In a cabinet a front wall having an opening therein, a panel mounted to close or open said opening, an electric lamp mounted within said cabinet adjacent said opening, a drawer movable forwardly and rearwardly, a radio receiving set in said drawer, said panel being located above said drawer so that 10 when said drawer is in forward position and said panel is open, the light from said lamp will be directed downwardly on said radio receiving set, a bull's eye in said panel for transmitting light from said lamp and an 15 annular handle pivoted on said panel and normally encircling said bull's eye.

7. A radio cabinet having a front door, a side door, said doors in their closed positions meeting at an angle at a corner of the cabinet, 20 an antenna on said side door, and hinges at the upper and lower ends of said doors, each of said hinges comprising a movable hinge member secured to and lying along the horizontal end surface of each of said doors, 25 the movable hinge members of each hinge having a common pivot offset from the corner of the cabinet and exterior of the planes of said doors, each of said hinges being secured to said cabinet and permitting movement 30 of each of said doors through an angle of substantially 270 degrees.

8. A cabinet having a front door, a side door, an antenna on said side door, and a hinge for said doors comprising a hinge member 35 on each of said doors, said hinge members having a common pivot offset from the corner of said cabinet and permitting movement of each of said doors through an angle of substantially 270 degrees.

40 9. A rectangular cabinet having a door normally disposed along the side of said cabinet, a fixed wooden cabinet portion extending beyond the outer face of said door when in its normal position, and a flat hinge member 45 secured to and set in the upper surface of said door and having an end projecting outwardly beyond the outer face of and beyond the end of said door and pivoted below the lower face of said fixed portion, permitting 50 said door to be swung through an arc of 270° to a position along an adjacent side of said cabinet.

MARTIN NYSTROM.
